UNITED STATES PATENT OFFICE

2,682,805

COMBINED MAGNIFIER AND CLEANING DEVICE

Edward J. Tomasovic, Chicago, Ill.

Application March 25, 1949, Serial No. 83,510

4 Claims. (Cl. 88—39)

1

This invention pertains to toys. More specifically it is directed to an improved type of a toy in the concealed squirt gun type.

Practical funsters have played so many various pranks that people are rather careful when approached by a person having a reputation for being a prankster. They suspect him always and accuse him of playing all the pranks. Innocent or not, he is always suspected and therefore anything he may try to show is always viewed with suspicion.

In order to overcome this suspicion and still carry on his pranks, the prankster has recourse to many devices that serve him well in friendly gatherings. Among these, I find my new device particularly useful and amusing.

My invention is not only amusing but also useful. It is not only a toy of the squirt gun type but also a useful magnifying lens that has its practical aspects. When not used as a toy, it has a small bellows that can be used to provide a small amount of air to blow dust off a covered surface and for other purposes that will be clear to any user.

It therefore is an object of my invention to provide a new and novel type of squirt toy that provides an immeasurable amount of joy and fun.

It is a further object of my invention to provide a magnifying glass that contains a small bellows in combination therewith to supply a small blast of air to the surface to be examined.

These and other objects, extensions, modifications, and variations thereof will be clearly apparent to those skilled in the art in light of the clear, accurate and lucid description given hereinbelow of the preferred embodiment which is further illustrated in the attached drawing forming a part thereof. It therefore, is not my intention to be limited directly or indirectly by the specific preferred embodiment described herein, since the same can manifestly be varied widely and still come within the spirit of the fundamental concepts underlying the principles of my invention.

Therefore Figure 1 in the attached drawing is a perspective view of my improved device.

Figure 2 is a plan view, while

Figure 3 is a sectional view of the same.

In the drawing the numerical characters indicating certain elements in the device refer to the same elements in the specification below.

My improved device consists of a case 10 which houses completely and protects the magnifying lens 12 retained in the rim 14. The glass re-

2

taining rim 14 has thereon an extension arm 16. The arm 16 and glass retaining rim 14 is pivotally mounted within the case 10 by means of a grommet-like tube 18 that serves as a pivot-shaft about which the retaining rim 16 can rotate.

One half of the outer edge of the case 10 has a downwardly projecting side or flange 20 that is sufficiently deep enough to cover not only the lens retaining rim 14 but also the bellows 22. 10 The other half of the outer edge of the case has an indentation therein to provide a finger rest or entry 24 on the rim 14. The rim 14, case 10, grommet-like tube 18 can be made of plastic or metal whichever is more desirable. The magnifying lens may be made of a clear plastic or glass.

The grommet-like tube 18 consists of an upper end 26 which penetrates the case 10 and is flared over the same to hold the case 10 securely in a pivoted juxtaposition about it. The lower end 28 is formed into a right angle bend whose end has a slight collar thereon.

A bulb or bellows 22 is provided and it is preferably made of molded plastic, rubber or thin flexible metal or materials that can be flexed so that a bellows action is obtained. In the bellows 22 is a chamber in which air, water or any other fluid medium is contained. The bellows has a neck 30 thereon which fits snugly over the collar on the end 28 of the tube 18. 20 Since the material forming the bellows 22 is resilient, it is therefore is obvious that when the bellows 22 are pressed, any fluid contained therein is outwardly ejected through the tube 18. 30 The bellows or bulb 22 is substantially similar in contour to the lens rim and is of a sufficient thickness, breadth and length to hold therein the desired quantity of a fluid. It, like the rim 14, pivots and is fitted within the cover together with the rim 14 to form a compact unit of convenient size and portability.

If the lens is to be used to observe an object, a prankster may fill the chamber of the bellows 22 with water and give the innocent victim or observer a squirt. However, under certain conditions, it is frequently desirable to observe the surface of some hairy object and in that case the opening of the tube 18 can be projected downwardly and a gentle draft produced on the object under observation by manipulating the bellows 22 to provide air with which to part the hair. Likewise, dust etc. can be blown off the surface under observation.

It is thus clearly obvious that my improved device can serve not only a useful purpose but

can also be applied in fun by pranksters as a toy. It therefore is not my intention to be limited to the preferred embodiment specifically described hereinabove and shown in the illustration, since it can be varied widely and still be within the ambit and spirit underlying the scope of the fundamental concepts of my invention as defined in the hereunto appended claims.

I claim:

1. A combined magnifier and cleaning device comprising a magnifying lens, a rim for said magnifying lens, an arm on said rim, a support through said arm which is rotatably mounted on said support, the said support comprising a grommet-like tube, one end of said tube flared over to retain the said arm in juxtaposition, an opening in the said flared end directing the egress of any fluid substantially perpendicular to the plane of said lens, the lower end of said tube bent at right angles to the said pivot and a bulb mounted on said right angle end whereby fluids contained in said bulb can be ejected when pressure is applied to said bulb.

2. A combined magnifier and cleaning device comprising a magnifying lens, a rim for said lens, an arm on said rim, a hollow tube about which the said arm is mounted, an opening in one end of said tube, the said opening capable of directing the fluid outwardly and substantially perpendicular to the said lens, the lower end of said tube having a right angle extension thereof, a bulb mounted on said extension, a housing in which the said lens and said bulb fit thereunder and a means on said tube to hold said rim arm, said bulb and said housing in juxtaposition.

3. A combined magnifier and cleaning device

comprising a magnifying lens, a rim for said lens, an arm on said rim, a hollow pivot means about which the said arm is pivotally mounted, an air bellows means attached to one end of said hollow pivot means, and a housing attached to the other end of said hollow pivot to contain the said lens, whereby air from the bellows produced by pressure of observer's fingers is directed upon the surface of the object under observation.

10 4. A combined magnifier and cleaning device comprising a magnifying lens, a rim to hold the same and rotatable about a support, a support through said rim, the said support comprising a right angled hollow tube, the vertical leg of said tube acting as a shaft for said rim, the horizontal leg of said tube having thereon a bulb, and a bulb for fluid attached to said horizontal leg and communicating internally with the vertical leg, whereby fluid within the bulb may be ejected 15 at the object under observation when pressure is applied to said bulb.
